FIG. 9.

FIG. 10.

Walter L. Kauffman II
INVENTOR.

BY *H. S. Land*
ATTORNEYS.

UNITED STATES PATENT OFFICE

2,065,330

WRINGER

Walter L. Kauffman, II, Erie, Pa., assignor to
 Lovell Manufacturing Company, Erie, Pa., a
 corporation of Pennsylvania

Application May 11, 1933, Serial No. 670,464

10 Claims. (Cl. 68—32)

Power wringers are preferably provided with some safety release mechanism. Some of such safety release mechanisms are provided with detachable tops and the release is effected by such detachment. Where this manner of release is utilized the violent projection of the top through the action of the pressure means of the wringer often carries the top away from the wringer to an objectionable extent. The present invention 5 is designed to arrest this movement after the top has moved a sufficient distance to properly release the pressure and involves devices for accomplishing this purpose which are simple and effective. The invention also contemplates devices for this purpose so formed that the top 10 may be readily detached to permit the convenient assembling and serving of the wringer. Features and details of the invention will appear from the specification and claims.

20 A preferred embodiment of the invention is illustrated in the accompanying drawings as follows:—

Fig. 1 shows a front elevation of the wringer, partly in section.

25 Fig. 2 a perspective view of one of the arresting bails, or straps.

Fig. 3 a front elevation of the wringer with the top in an intermediate position showing the manner of detaching the top.

30 Fig. 4 a perspective view of the upper end of the stile with the parts removed.

Fig. 5 a sectional view of the strap and upper part of the stile.

35 Fig. 6 a section on the line 6—6 in Fig. 1.

Fig. 7 a sectional view showing one of the arresting bars, or straps in arresting engagement with the stile.

40 Fig. 8 a section on the line 8—8 in Fig. 1.

Fig. 9 is an enlarged sectional view of the top bar and release mechanism.

45 Fig. 10 a perspective view of the release latches.

Fig. 11 a view of the releasing mechanism as the top bar is replaced.

50 The wringer frame is made up of the base 1, and side stiles 2. These are preferably formed of sheet metal, the side stiles being of box form. Wringer rolls 3 and 4 have the usual shafts 5 and 6 and these are journaled in bearing blocks 7 and 8 mounted in the side stiles. A spring 9 operates on the upper end of the upper bearing block and is put under tension by a screw 10 operating in a nut 11, the nut being carried by the top 12. The top 12 is of channel form and 55 sets over the tops of the stiles and is detachable

therefrom. The structure so far described is similar in most respects to wringers now in use. Hooks 13 are formed on the ends of latches 14, the latches being journaled on rods 15 extending across the top. These hooks engage shoulders 16 formed by slots in the side stiles. The latches have projecting ends 17 which are adapted to engage the top of the side stile as the wringer top is put in place, this projection tending to swing the hooks into interlocking position. The 10 inner ends 19 of the latches 14 extend under ends 19 of a swinging trip plate 20. The trip plate has pivotal ears 21 which extend into slots 22 in brackets 23 welded, or secured to the under-side of the wringer top. The plate 20 has 15 slots 20a at each side of the screw 10 into which projects a lip 24 formed in the plate. Cross bars 25 extend through slots 26 in the sides of the top and through the slots 20a in the trip plate. The cross bars 25 have perforations 27 20 which receive the lips 24 and thus lock these cross bars with the trip plate. Operating bars 27a are formed on the ends of the bars 25.

In order to effect a release of this mechanism the operator hits the bar 27a. This swings the 25 trip plate, releases the latches 14 and these swinging up release the hooks 13 and thus release the top. The full force of the spring is back of this release and violently throws the top upwardly. Inasmuch as the free release to 30 a point that will relieve pressure is desirable the immediate removal of pressure from the spring is effective.

It is desirable, however, to prevent the complete discharge of the top from the wringer which, under the impulse of the spring, might be carried for a considerable distance. To accomplish this the present mechanism is provided. Side straps, or bars 28 are connected by a cross piece 28a at the bottom, these being 35 formed preferably of a single stamping and thus in the final shape are bail-shaped. These bails are slidingly mounted in and guided by the walls of the side stiles and loop around the ends of the upper shaft of the roll and form sliding 40 guides for the upper bearing blocks 8, the sides of the bails being provided with inturned lips 29 to complete the guides for the bearing blocks. The upper ends of the bails have inwardly extending projections 30 which are provided with 45 elongated slots 31 through which the rods 15 extend. The pivotal connection between the bails and the cross bar is desirable particularly where the bails extend into the side stiles in that if one side only of the cross bar is released 50 55

it permits a free upward movement, the pivotal movement permitting the angular arrangement of the top bar relatively to the bail and this is further accommodated by the elongated slot 5 which gives lateral freedom between the top and the bail as the bail is guided upwardly in the stile. If both ends of the cross bar are released this pivotal arrangement is also desirable as there is often an unevenness in the upward 10 movement by reason of the engagement of the operator's hand and the pivotal movement assures a free release regardless of the departure of the top from a horizontal position. The upper ends of the stiles have inturned arresting lips 15 32 which are in the paths of the cross pieces 28a of the bails as the bails are moved upwardly in the side stiles. The lower end of the bail extends below the upper bearing blocks, as clearly shown in Figs. 1 and 2 so that there is a free 20 movement upwardly of the top bar for some distance before the upper roll shaft is engaged.

The operation of these arresting bars, or bails, is as follows:—When the top is released to effect a release of the pressure on the rolls the top 25 in its upward movement carries with it the suspended bails 28. These bails pick up the upper roll in the upward movement, thus not only immediately relieving all pressure from the operator who may be caught, but also retarding 30 to some extent the violent up-throw of the top. With the further upward movement of the top the cross pieces of the bails engage the lips 32 and the top is thus definitely arrested. All that is necessary to re-set the wringer is to release 35 the pressure on the spring, trip the top back into position so that the latches catch and then set the tension on the spring.

It is desirable to have the top readily removable and this is accomplished in the present 40 structure by forming the lips 32 adjacent the top of the stile so that by tilting the bails with a side-swinging movement, as shown in Fig. 3, the inner edge of the bail will clear the opposite top edge of the stile so that the bail can be 45 swung clear of the lip 32. By swinging the top in one direction one of the bails may be released and by reversing the movement in the opposite direction the opposite bail can be readily released.

50 **What I claim as new is:—**

1. In a wringer, the combination of a frame having side stiles; rolls having shafts mounted in the stiles; pressure means for the rolls; a top for the frame receiving the counter-pressure 55 from the pressure means; a safety release device detachably securing the top on the frame; and bails pivotally secured to the top and looping the upper roll shafts, said bails and stiles having interlocking arresting parts limiting the upward movement of the top as it is released.

60 2. In a wringer, the combination of a frame having side stiles; rolls having shafts mounted in the stiles; pressure means for the rolls; a top for the frame receiving the counter-pressure 65 from the pressure means; a safety release device detachably securing the top on the frame; and bails pivotally secured to the top and looping the upper roll shafts, said bails and stiles having interlocking arresting parts limiting the upward movement of the top as it is released, 70 said parts being detachable.

75 3. In a wringer, the combination of a frame having hollow side stiles; rolls having shafts mounted in the stiles; a detachable top arranged on the stiles; bails pivotally secured to the top

and extending into the stiles and looping the ends of the upper roll shafts; bearing blocks for the upper shaft slidably mounted in said bails; roll pressure means exerting counter-pressure on the top; a safety release acting by 5 releasing the top; and interlocking parts between the bails and stiles limiting the upward movement of the top when released.

4. In a wringer, the combination of a frame having side stiles; wringer rolls; bearings for 10 said rolls mounted in the stiles; a top for the frame; a spring between the top and the upper bearings exerting pressure on the bearings and counterpressure on the top; a safety release device detachably securing the top on the frame at 15 least at one end of the top; and top arresting means slidably mounted in and having guiding engagement with a wall of a stile, said means directly locking with the stile limiting the upward movement of the top upon release. 20

5. In a wringer, the combination of a frame having side stiles; wringer rolls; bearings for 25 said rolls mounted in the stiles; a top for the frame; a spring between the top and the upper bearings exerting pressure on the bearings and counterpressure on the top; a safety release device detachably securing the top on the frame at both ends of the top, and top arresting means 30 slidably mounted in and having guiding engagement with the walls of each stile, said means locking directly with the stiles limiting the upward movement of the top upon release.

6. In a wringer, the combination of a frame having side stiles; wringer rolls; bearings for 35 said rolls mounted in the stiles; a top for the frame; a spring between the top and the upper bearings exerting pressure on the bearings and counterpressure on the top; a safety release device detachably securing the top on the frame at least at one end of the top; and top arresting means 40 slidably mounted in a stile, said means locking directly with the stile limiting the upward movement of the top upon release, said arresting means being movable relatively to the top bearing. 45

7. In a wringer, the combination of a frame having side stiles; rolls mounted in the stiles; pressure means for the rolls; a top for the frame receiving the counterpressure from the pressure means; a safety release device detachably securing the top on the frame at least at one end of the top; and top arresting means 50 slidably mounted in and having guiding engagement with the walls of a stile, said means locking with the stile limiting the upward movement of the top upon release, said means having a pivotal connection with the top. 55

8. In a wringer, the combination of a frame having side stiles; rolls mounted in the stiles; pressure means for the rolls; a top for the frame receiving the counterpressure from the pressure means; a safety release device detachably securing the top on the frame at least 60 at one end of the top and top arresting means slidably mounted in and having guiding engagement with the walls of a stile, said means locking with the stile limiting the upward movement of the top upon release, said means having a pivotal connection with the top, said connection having lateral freedom. 65

70 9. In a wringer, the combination of a frame having a base and side stiles forming a U shaped structure open at the top; rolls mounted in the stiles; pressure means for the rolls; a top bar mounted on the stiles receiving the counter- 75

pressure from the pressure means; a safety release device detachably securing the top bar; and an arresting device pivotally secured to the top bar and extending into a stile, said device and stile having directly engaging, interlocking parts limiting the upward movement of the top as it is released.

5. 10. In a wringer, the combination of a frame having hollow side stiles, rolls having shafts

mounted in the stiles, a detachable top arranged on the stiles, a bail pivotally secured to the top and extending into the stile and guided thereby and looping the end of the upper roll shaft, a bearing block for the upper shaft slidingly mounted in said bail, and means on the bail forming a guideway on the bail for holding the bearing block in sliding relation.
